United States Patent

Des. 242,017
Patented Oct. 26, 1976

242,017

BOTTLE

Raymond G. Reynolds, Sylvania, Ohio, assignor to Owens-Illinois, Inc., Toledo, Ohio

Filed June 17, 1974, Ser. No. 479,816

Term of patent 14 years
The term of this patent subsequent to Oct. 26, 1990, has been disclaimed

Int. Cl. D9—01

U.S. Cl. D9—10

FIG. 1 is a front elevational view of a bottle showing my new design;

FIG. 2 is a rear elevational view of the bottle of FIG. 1; and

FIG. 3 is a sectional view, taken along line 3—3 of FIG. 2.

I claim:

The ornamental design for a bottle, substantially as shown.
